UNITED STATES PATENT OFFICE

141,149

DESIGN FOR A COMBINED CIGARETTE AND MATCH CASE

Jack B. Nethercutt, Santa Monica, Calif.

Application August 5, 1944, Serial No. 114,747

Term of patent 14 years

(Cl. D85—2)

To all whom it may concern:

Be it known that I, Jack B. Nethercutt, a citizen of the United States, residing in the city of Santa Monica, county of Los Angeles, and State of California, have invented a new, original, and ornamental Design for a Combined Cigarette and Match Case, of which the following is a specification, reference being had to the accompanying drawing, forming a part thereof.

The drawing is a perspective view of the combined cigarette and match case showing my new design. The rear and side not shown are plain.

The ornamental design for a combined cigarette and match case, as shown and described.

JACK B. NETHERCUTT.
